UNITED STATES PATENT OFFICE

2,416,383

OIL BURNER

Francois Uldege Dumas, Spencer, Mass.

Application March 4, 1944, Serial No. 524,990

3 Claims. (Cl. 158—87)

1

Objects of the invention include the provision of a novel and improved oil burner including an improved means for priming, comprising an oil reservoir located adjacent to a device which will quickly preheat the oil; the provision of an improved oil burner including an interior heating chamber which will preheat the oil prior to burning and will thus improve the action of the burner and economy in burning; and the provision of a more economical oil burner providing novel means for air intake and increasing the air directed to the flame area.

Other objects and advantages of the invention will appear hereinafter.

Reference is to be had to the accompanying drawings, in which

Fig. 1 is a vertical section through a device according to the invention;

Fig. 2 is a detail perspective view of a modification thereof;

Fig. 3 is a view similar to Fig. 2 showing a further modification.

In the drawings the reference character 10 represents a support on which the oil burner is to be mounted and this is accomplished by securing a circular sheet metal skirt 12 to the support. I provide a bottom element 14 which includes a depending part 16 providing a chamber 18 for the oil and which is connected to the oil reservoir by means of a pipe 20. A ball arrangement 22 is provided for use in mounting the bottom element 14 on a stand or bracket.

The chamber 18 extends vertically and opens into a cup-shaped reservoir at 24 formed by the interior surface of the bottom element 14. The oil will be fed upwards to the point of vaporization along the entire surface of the interior of element 14 and will be guided by a sheet metal element 26 which has a shape conforming to the cup-shape of element 14. The element 26 is spaced from element 14 to provide the passage 28 for the oil. Element 26 is raised as shown at 30 to provide a reservoir for the oil for a purpose to be described, it being understood that element 14 and element 26 are circular in shape, and a vent 34 is provided.

At the upper limit of the element 14, I provide a circular channel 32 which may contain a wick if desired. The element 26 terminates in a flange 24 which supports a cylindrical closed element 36, the latter being open at the bottom and closed at the top by a plate 38. Plate 38 is supported on the element 36 as shown, and independently mounts a perforated cylinder 40 which extends down and stops just short of the opening of

chamber 28 as is clearly shown in Fig. 1. An exterior perforated cylinder 42 is mounted on element 14 by means of a shoulder 44 and the cylinder 42 is closed at the top by a perforated plate 46. The skirt 12 is secured to the exterior of cylinder 42 as shown in Fig. 1 and is larger than the diameter of element 14, being bent in at its top as at 48 to be secured. This arrangement provides that an air draft will be directed from the bottom of the burner directly to the combustion zone at the exterior of element 14, the draft being restricted to enter between cylinders 42 and 40, since the skirt 12 and element 14 are imperforate. This draft enters the space between cylinders 40 and 42 through a series of holes 50. Centrally of plate 38 I provide a cylinder 52 which depends therefrom and extends lower than the other cylinders, stopping just short of the upper part of the bulge 30 for the purpose of preheating oil located within this bulge.

In the operation of the burner the best draft possible will be induced between skirt 12 and the element 14 and this draft will be directed exactly to the point of burning of the oil. The oil is led up through chamber 28 and issues in vaporized state under the lower edge of cylinder 40. The imperforate cylinder 38 will obviously become heated to a high degree and will cause the cup-shaped chamber formed by element 26 to be highly heated whereby the oil in chamber 28 will become quickly preheated increasing the vaporization and economy in burning oil. In addition, the central cylinder 52 will cause the same effect to an increased degree and the heat in cylinder 52 will be directed to the bulge 30 thus increasing the heating of the oil contained therein. The construction above described will greatly contribute to economy of burning of the oil and will also contribute to ease in maintaining the burner in good operating condition. The modification of Fig. 2 dispenses with channel 32 and instead provides air channels 54 leading from the air draft between skirt 12 and element 14 directly to the oil vaporizing area so that the wick may be dispensed with and the draft increased.

Fig. 3 is a modification of the Fig. 2 device and provides in addition to the construction there shown a series of oil receiving recesses 56 which are connected by a channel or the like 58 for passage of the oil from recess to recess.

The construction of Figs. 2 and 3 will provide sufficient air so that the wick is not necessary, the issuing oil being immediately vaporized and burned and for this reason it may be that in some

instances it will be convenient to dispense with holes 50 and secure skirt 12 at a point 60 as shown in Fig. 3, thus forcing all the air up through passages 54. This construction may be used in either the case of Fig. 2 or Fig. 3.

Having thus described my invention and the advantages thereof, I do not wish to be limited to the details herein disclosed, otherwise than as set forth in the claims, but what I claim is:

1. An oil burner structure comprising a base element in the shape of a cup, a cup-shaped element interiorly of the base element and spaced therefrom to provide a passage for oil between said elements, oil inlet means in the base element to supply oil to said passage, an upstanding perforated cylinder on the base element, a coaxial perforated cylinder of smaller diameter mounted with the lower edge thereof between and slightly spaced from the base element and the second named element, a depending imperforate skirt surrounding the base element in spaced relation thereto, and secured adjacent to the lower edge of the first named cylinder to provide an air chamber between the skirt and base element, said burner structure being provided with air passages from the air chamber to the space between the two perforated cylinders.

2. An oil burner structure comprising a base element in the shape of a cup, a cup-shaped element interiorly of the base element and spaced therefrom to provide a passage for oil between said elements, oil inlet means in the base element to supply oil to said passage, an upstanding perforated cylinder on the base element, a coaxial perforated cylinder of smaller diameter mounted with the lower edge thereof between and slightly spaced from the base element and the second named element, a depending imperforate skirt surrounding the base element in spaced relation thereto, and secured adjacent to the lower edge of the first named cylinder to provide an air chamber between the skirt and base element, the base member being provided with air passages from the air chamber to the space between the two perforated cylinders.

3. An oil burner structure comprising a base element in the shape of a cup, a cup-shaped element interiorly of the base element and spaced therefrom to provide a passage for oil between said elements, oil inlet means in the base element to supply oil to said passage, an upstanding perforated cylinder on the base element, a coaxial perforated cylinder of smaller diameter mounted with the lower edge thereof between and slightly spaced from the base element and the second named element, a depending imperforate skirt surrounding the base element in spaced relation thereto, and secured adjacent to the lower edge of the first named cylinder to provide an air chamber between the skirt and base element, the wall of the first named cylinder being provided with air passages from the air chamber to the space between the two perforated cylinders.
